UNITED STATES PATENT OFFICE.

THOMAS P. NELSON, OF HARRISBURG, PENNSYLVANIA.

TARGET.

SPECIFICATION forming part of Letters Patent No. 473,332, dated April 19, 1892.

Application filed August 14, 1891. Serial No. 402,609. (No model.)

To all whom it may concern:

Be it known that I, THOMAS P. NELSON, a citizen of the United States, residing at Harrisburg, in the county of Dauphin and State 5 of Pennsylvania, have invented certain new and useful Improvements in Military Targets; and I do declare the following to be a full, clear, and exact description of the invention, such as will enable others skilled in the art to 10 i which it appertains to make and use the same, reference being had to the accompanying drawings, and to the figures of reference marked thereon, which form a part of this specification.

15 My invention relates to improvements in military targets; and the objects of the invention are, first, to provide an improved target which is impenetrable to the bullets or shot of a rifleman shooting at a range and 20 20 which is readily adjustable or convertible into a long or short range target—as, for instance, a three-hundred, four-hundred, five-hundred, or six-hundred yards target or an eight-hundred, nine-hundred, or one-thousand 25 yards target; second, to provide secure protection to the marker or attendant who is stationed near the target to signal the marksman the result of the shooting, and, finally, to enable the marker to signal the nature or 30 30 result of the shot to the rifleman with entire safety to the marker and without the least danger to the marker unless through his own carelessness.

With these and other ends in view my invention 35 consists in the novel combination of devices and peculiar construction and arrangement of parts, which will be hereinafter fully described, and pointed out in the claims.

To enable others to understand my invention 40 40 I have illustrated the same in the accompanying drawings, in which—

Figure 1 is a front view of a military target embodying my invention. Fig. 2 is a side view thereof, said views showing the target 45 45 in position for use. Fig. 3 is a rear elevation of the target, showing the same in position for use. Fig. 4 is a sectional view through the target on the line xx of Fig. 1. Fig. 5 is a sectional view somewhat similar to Fig. 4, 50 50 but showing the target folded up. Fig. 6 is a detail view of the score-signaling device. Fig. 7 is a detail view of the shield for pro-

tection the marker while engaged in obliterating the marks or abrasions on the face of the target due to the shot striking the same, 55 and Fig. 8 is a detail view of the brush for applying paint to the target.

Like numerals of reference denote corresponding parts in the several figures of the drawings, referring to which—

1 designates the target plate or sheet, which is made or composed of a single piece of steel of suitable size and of sufficient thickness to prevent the bullets from penetrating the same.

In my improved military target I use a metallic impenetrable sheet or plate, as distinguished from paper, wood, or other materials which require constant renewing after being in use for a short time. Besides, the metallic 70 sheet affords greater protection to the marker or attendant stationed at the target to signal the rifleman the result of the shooting, thereby dispensing with the construction of "butts" for shielding the marker from the bullets. 75 This metallic plate or sheet 1 is provided on both sides with the usual concentric rings and center constituting the diagram or chart for the rifleman to aim at, and this metallic sheet or plate is mounted so as to be reversed or inverted to bring the different charts into position, and thereby adapt the target for long and short ranges. The rings or diagram on each side of the target plate or shield is formed by grooving or cutting out the design in the 80 metal of the plate or sheet, after which the rings and center are coated with paint of one color, while the body or remaining portion of the sheet is coated with another color suitable for bringing out the design or chart. Thus 85 the rings and center may be painted black and the body of the target white, as is usual, or any other combination of colors may be used.

The target plate or shield is arranged and 95 hung within a suitable stout frame 2 of wood or any other suitable material in a manner which permits or insures ready reversal of the sheet to bring either of the two diagrams or charts into position for use. Thus the diagram 100 on one side is smaller than the diagram on the opposite side of the plate or sheet, the one being adapted to short-range firing, while the other to long-range firing. The frame 2 is

constructed in a substantial and durable manner, and said frame is somewhat larger in area or size than the sheet or plate 1 to provide a continuous opening or space 3 entirely around the target sheet or plate and between the same and the frame for the purpose of swinging or reversing the plate or sheet. This reversible sheet or plate is hung on trunnions 4, 5, which are rigidly attached to the plate or sheet and which work or are journaled in steel washers or bearings 6, which are rigid with the substantial frame 2. The manner of arranging the trunnions or pivots and the connection of the several parts are not material, although I prefer to use the horizontal trunnions, as shown in the drawings; but it is evident that the trunnions and bearings therefor can be placed vertically without departing from the spirit of my invention.

In order to hold or keep the target sheet or plate in position and at the same time prevent a bullet from passing through the space 3 between the reversible sheet and the frame 2, provided for the support of the sheet, I resort to the use of the closing-strips 7, 8, 9, and 10 and the swinging doors 11, 12, which effectually close said opening or space and serve to protect the marker or attendant from being injured by a bullet while he is stationed behind the target. The strips are all arranged at the front side of the target, while the doors are on the rear side of the target, and said strips and doors are made of steel or other metal of suitable thickness and width to prevent a bullet from penetrating the same. The top strip 7 is hinged to the upper part of the frame 2 to be thrown upwardly above the target-sheet. The side strips 8, 9 are arranged on the right and left hand sides of the target-sheet and hinged to the frame 2, so as to be swung or turned outwardly to the side of the sheet or plate 1, and the bottom strip 10 is hinged to the lower edge of the frame 2, so as to be turned downward. When the several strips are turned away from the sheet or plate, the latter can be reversed or swung around, provided the doors 11, 12 at the rear are thrown open, and after the sheet or plate has been reversed the strips are closed or folded in the following order: The bottom strip 10 is turned upward, the two side strips are turned inward, and the top strip 7 is turned downward, the lower ends of the side strips lapping the bottom strip and the top strip overlapping the upper ends of the two side strips. I do not, however, wish to confine myself strictly to this precise arrangement of the strips, although I prefer to adopt or use the same, because I have found by experience that the strips effectually hold the sheet or plate, in position when a bullet strikes the same, and at the same time the space 3 is effectually closed to prevent a bullet from passing to the rear of the sheet or plate.

The doors 11, 12 are hinged to the sides of the frame 2, and they are adapted to be opened or thrown outward, so as to provide room or

space for reversing the target. The doors are arranged to meet in the middle of the target sheet or plate, although they do not come in contact or engagement therewith, and when closed the doors are confined in place by a suitable fastening 13. I also use a catch or fastener 14 within the frame 2, which is adapted to engage with the edge of the sheet or plate 1 and to hold the same in a fixed steady position.

The doors 11, 12 are arranged some distance in rear of the reversible sheet or plate 1, so as to leave a space or chamber 15 between the sheet or plate and the doors when the latter are closed, and this space is utilized for the storage of the signaling device, the flags, paint-pots, &c., when the target is not in use.

The signaling device consists, essentially, of a box or casing 17, a series of disks 18, and a common shaft or pin 19, which passes through the casing and the disks to pivotally connect the disks to the casing and enable the marker to adjust or expose any one of the disks. The casing is provided on one side with lugs or ears 20, which have openings or holes to receive fixed pins on the frame 2 of the target, thereby enabling the marker or attendant to hang or suspend the casing in the rear of the target, where he can operate either one of the disks to expose the same to the view of the marksman or rifleman and indicate to the latter the number of points or the position where the bullet struck the target. The casing is suspended or hung on the frame 2, so that the signal-disks can be elevated above the target; but it is obvious that the casing may be suspended on the target-frame to expose the disks on either side thereof.

Each disk is provided with an extended handle or arm 22, and the disks and arms are arranged closely together within the casing, so that the signaling device takes up little room. Each arm or handle has a depending pull-wire 24, which are of different lengths to enable the attendant to readily select the disk to be exposed. The disks are painted different colors to denote the different points or the results of the shots striking the target. Thus one disk may be painted white to denote the "bull's-eye" or center of the target. Another disk may be painted red to denote that the bullet struck the first ring outside of the center. Another may be painted half white and half black to denote the shot struck the target within the second ring. Another entirely black to denote if the bullet struck outside of the ring, and so on. It is evident the color of the different signal-disks can be varied with the code of signals that may be adopted, and I do not therefore restrict my invention to the use of disks of any particular color.

As a further protection to the attendant or marker, I have devised a metallic shield 25, which is substantially V shape or of other angular or curved shape in cross-section. This fixed shield is arranged with its angular or curved side outward, facing the range, and at

one side of the target a little in advance thereof. The shield may be placed on the right or left hand side of the target and planted in the ground or held in position by stakes 27, driven through sockets or ways 28 in the edges of the shield. The marker may be stationed either behind the target or behind the shield, which is arranged a little in advance of the target, and when behind the target he signals the rifleman that he will step from behind the target into position behind the shield to prevent the rifleman from firing while he is obliterating the marks on the face of the target caused by the bullets striking the same. The attendant can efface the bullet-marks and at the same time indicate the position of the mark to the rifleman by means of a small brush 30, which passes through a disk 31, fixed to the end of a long handle or staff 32, as indicated in Fig. 8 of the drawings.

The operation of my invention may be briefly described as follows: The marker takes position behind the shield or the target and the marksman fires at the target. The attendant behind the advanced shield can readily observe the position of the shot and by displaying the proper signal inform the rifleman the point where the shot struck the target, indicating the number of points scored. The attendant also can obliterate the bullet-mark by the brush and at the same time notify the rifleman the point the bullet hit the target. If it is desired to vary the range of firing, the firing-point can be moved nearer or farther away, and the sheet or plate should be properly adjusted to expose the diagram which corresponds to the range. Thus if a short range is used the strips and doors are thrown open and the sheet reversed to display the smaller diagram or chart; but if the range is increased the sheet is adjusted to expose the larger diagram or chart, the strips and the doors being always closed before permitting the rifleman to resume firing.

I am aware that changes in the form and proportion of parts and details of construction

of the mechanism herein shown and described as an embodiment of my invention can be made without departing from the spirit or sacrificing the advantages of my invention.

Having thus described my invention, what I claim as new, and desire to secure by Letters Patent, is—

1. In a military target, the combination, with an open frame, of a reversible plate or sheet pivotally supported therein and the adjustable barriers arranged to close the spaces between the open frame and the sheet or plate, substantially as and for the purpose set forth.

2. In a military target, the combination, with an open frame, of the reversible sheet or plate, pivotally supported in said open frame and the barrier-strips connected to said frame and arranged to close the spaces between the frame and the sheet or plate, said sheet having on its reverse faces suitable designs, as and for the purpose described.

3. In a military target, the combination of an open frame, a sheet or plate pivoted therein, and the movable strips for closing the space between the sheet and frame, substantially as described.

4. In a military target, the combination of an open frame, a sheet or plate reversible therein, and the adjustable strips hinged to the frame and arranged when closed to overlap each other, substantially as described.

5. In a military target, the combination of an open frame, a sheet or plate reversible therein, the hinged strips at the front of the frame and arranged to close the space between the frame and the sheet, and the doors at the back of the target, substantially as described.

In testimony whereof I affix my signature in presence of two witnesses.

THOMAS P. NELSON.
